CLAIM

The ornamental design for a pod for a beverage mixing system, as shown and described.

DESCRIPTION

FIG. 1 is a top perspective view of a pod for a beverage mixing system according to an embodiment of the present invention.

FIG. 2 is a bottom perspective view of the pod for a beverage mixing system shown in FIG. 1.

FIG. 3 is a plan view of the top of the pod for a beverage mixing system shown in FIG. 1.

FIG. 4 is an elevational view of a side of the pod shown in FIG. 1. Due to its circular shape, the other side views of the pod are identical to that shown in FIG. 4; and,

FIG. 5 is a plan view of the bottom pod for a beverage mixing system shown in FIG. 1.

It is contemplated that any one or more of the solid lines shown in any one or more of the Figures can be converted into broken lines to form no part of a claimed invention. The break lines shown in various ones of the Figures are only for illustrative purposes to indicate that the appearance of any portion of the illustrated article between the solid lines form no part of the claimed invention.
